UNITED STATES PATENT OFFICE

EDWARD THOMAS MORRIS, OF LONDON, ENGLAND, ASSIGNOR TO R. HOE & CO. INC., OF NEW YORK, N. Y., A CORPORATION OF NEW YORK

SHEET-INSETTING MECHANISM FOR ROTARY MULTIPLE-WEB-PRINTING MACHINES

Application filed July 24, 1926, Serial No. 124,737, and in Great Britain July 29, 1925.

This invention relates to sheet insetting mechanism for rotary multiple web printing machines.

In a sheet insetting machine of this kind, when a sheet from one printing mechanism is inset between two sheets from another printing mechanism, it is usual to drive the mechanism printing the sheet to be inserted at a speed slower than (say half of) that of the mechanism for printing the other two sheets. The sheet to be inset is fed by friction rollers or the like, acting in conjunction with a cutting cylinder, towards a collecting cylinder which takes charge of the sheets. At the moment that the sheets are taken in charge by the collecting cylinder, the sheet which is to be inset is freed from its cutting cylinder and rollers, by moving these latter away from the said cutting cylinder. Such mechanism, as a rule, is found to work satisfactorily up to a certain speed, but if the printing machine be driven at a higher speed, so as, for example, to handle 10,000 copies an hour, it is found that the sheet may not be inset in proper position.

According to the present invention I provide in a machine as set forth above, for the sheet to be inset, additional feeding means between the usual feeding device and the collecting cylinder.

In one form of construction such additional feeding means comprises friction rollers, parts of whose peripheries are stepped back, the arrangement being such that the sheet to be inset is disengaged at the moment it is taken in charge by the collecting cylinder.

It is obvious that either one or both of the coacting pairs of such rollers may have their periphery or peripheries stepped back.

In the accompanying diagrammatic view which illustrates the invention, 1 is a paper web which is led around a roller 2 and passes between cutting cylinders 3, 4, the cylinder 3 having a knife 5 which registers once during each revolution with a gutter 4' in the cylinder 4. 6 is a collecting cylinder provided with sheet taking devices, as pins 6', and 7 is a cylinder which delivers sheets from the cylinder 6 to folding mechanism (not shown). A second web 8 is led (at half the speed of

the web 1) around a roller 9 and is passed between cutting cylinders 10, 11, the cylinder 10 having a knife 12 which registers once during each revolution with a gutter 11' in the cylinder 11. The web 8 is led from between the cylinders 10, 11 and a roller 13 and cylinder 11, to guides 14, 15 and friction rollers 16, 17, running at the speed of the high speed web part of whose peripheries are stepped back at 18, 19.

In operation, the web 1, passing between the cylinders 3, 4, is cut by the knife 5, the portion thus severed passing around the cylinder 6; after the cylinders 3, 4 have completed another revolution, the web, following the trailing edge of the severed portion, is cut by the knife 5, the leading edges of this sheet and the sheet previously severed meeting as they pass into the nip of the rollers 4, 6. Simultaneously with the meeting of the leading edges of the said sheets, the leading edge of a sheet which has been severed from the web 8 by the knife 12 is fed by the friction rollers 16, 17, between the first mentioned sheets, so that the leading edges of the three sheets enter the nip of the cylinders 4, 6 together. At this moment the sheet from the web 8 is released from the rollers 16, 17, by the alinement of the stepped back portions 18, 19.

The two sheets from the web 1 with the third sheet from the web 8, are then delivered to folding mechanism by the cylinders 6, 7.

What I claim is:

1. In a sheet insetting machine, the combination of cutting cylinders, a collecting cylinder, means in addition to and cooperating with the cutting cylinders for feeding the sheet to be inset from said cutting cylinders to said collecting cylinder, and additional means running at the speed of the collecting cylinder for feeding the sheet to be inset located between the first said means and the collecting cylinder and having provision for releasing the sheet.

2. In a sheet insetting machine, the combination of cutting cylinders, a collecting cylinder, means for feeding the sheet to be inset from said cutting cylinders to said collecting cylinder, and additional means run-

ning at the speed of the collecting cylinder for feeding the sheet to be inset located between the first said means and the collecting cylinder, comprising a friction roller having part of its periphery stepped back.

3. In a sheet insetting machine, the combination of cutting cylinders, a collecting cylinder, means for feeding the sheet to be inset from said cutting cylinders to said collecting cylinder, and additional means running at the speed of the collecting cylinder for feeding the sheet to be inset located between the first said means and the collecting cylinder, comprising a pair of friction rollers, one 10 of said rollers having part of its periphery stepped back.

4. In a sheet insetting machine, the combination of cutting cylinders, a collecting cylinder, means for feeding the sheet to be inset from said cutting cylinders to said collecting cylinder, and additional means running at the speed of the collecting cylinder for feeding the sheet to be inset located between the first said means and the collecting cylinder, comprising a pair of friction rollers each having part of its periphery stepped back.

5. In a sheet insetting machine, the combination of a collecting cylinder, cutting cylinders comprising a gutter cylinder and a knife cylinder, a friction roller adapted to co-operate with said gutter cylinder for feeding the sheet to be inset to said collecting cylinder, and additional means running at the speed of the collecting cylinder for feeding the sheet to be inset located between the gutter cylinder and friction roller co-operating therewith and the collecting cylinder.

6. In a sheet insetting machine, the combination of a collecting cylinder, cutting cylinders comprising a gutter cylinder and a knife cylinder, a friction roller adapted to co-operate with said gutter cylinder for feeding the sheet to be inset to said collecting cylinder, and additional means running at the speed of the collecting cylinder for feeding the sheet to be inset located between the gutter cylinder and friction roller co-operating therewith and the collecting cylinder, comprising a friction roller having part of its periphery stepped back.

7. In a sheet insetting machine, the combination of a collecting cylinder, cutting cylinders comprising a gutter cylinder and a knife cylinder, a friction roller adapted to co-operate with said gutter cylinder for feeding the sheet to be inset to said collecting cylinder, and additional means running at the speed of the collecting cylinder for feeding the sheet to be inset located between the gutter cylinder and friction roller co-operating therewith and the collecting cylinder, comprising a pair of friction rollers, one of said rollers having part of its periphery stepped back.

8. In a sheet insetting machine, the combination of a collecting cylinder, cutting cylinders comprising a gutter cylinder and a knife cylinder, a friction roller adapted to co-operate with said gutter cylinder for feeding the sheet to be inset to said collecting cylinder, and additional means running at the speed of the collecting cylinder for feeding the sheet to be inset located between the gutter cylinder and friction roller co-operating therewith and the collecting cylinder, comprising a pair of friction rollers each having part of its periphery stepped back.

9. In a sheet insetting machine, the combination of cutting cylinders, a collecting cylinder, means co-operating with the cutting cylinders for feeding the sheet to be inset from the cutting cylinders to the collecting cylinder, and additional means running at the speed of the collecting cylinder for feeding the sheet to be inset thereto, comprising a pair of friction rolls having sheet holding surfaces of the same diameter as the collecting cylinder, and located between the first feeding means and the cylinder and provided with means for releasing the sheet.

10. In a sheet insetting machine, the combination of cutting cylinders, a collecting cylinder, means cooperating with the cutting cylinders for feeding the sheet to be inset from the cutting cylinders to the collecting cylinder, and additional means running at the speed of the collecting cylinder for feeding the sheet to be inset thereto, comprising a pair of friction rolls located between the first means and the collecting cylinder, the rolls having sheet holding surfaces of the same diameter as the collecting cylinder, and one of the rolls having its periphery stepped back.

In testimony that I claim the foregoing as my invention, I have signed my name this 13th day of July, 1926.

EDWARD THOMAS MORRIS.
